Application October 26, 1936, Serial No. 107,741
In Germany November 1, 1935

12 Claims. (CL. 60—54)

This invention relates to control means for emptying the working circuits of fluid power transmitters and its object is to render the regulation and emptying of these rotating chambers controllable at will and to permit the working fluid to be exhausted as rapidly as possible.

With previously known hydraulic power transmitters, in many cases the emptying of the working circuits was effected simply by ports in stop-valve devices which were adapted to keep the circuits sealed during running. With other arrangements, in which the leakage loss occurring during running is compensated by means of a charging pump, this pump is merely stopped to effect emptying, and the working circuit exhausts through the gap between the vane wheels or through small ports at the periphery, under the action of centrifugal force. In other cases again, a closable port was provided at the periphery of the rotating part of the transmitter in the neighborhood of its maximum diameter and leading directly from the working chamber into the open, especially for the purpose of obtaining automatic and accelerated emptying. These devices have, however, the objection that relatively heavy parts, guided in suitable guides, are necessary for controlling the emptying ports. Firstly, owing to the radially acting centrifugal force, additional pressure is needed to keep the stop-valve parts shut, since these tend to move outwards by reason of their mass. Further, there is the risk that these stop-valve parts, which are guided in guides, will seize with the slightest fouling produced by the working fluid and thus adversely affect the effectiveness of the emptying device and in consequence interfere with the operation of the whole fluid transmitter.

The present invention has, in comparison with these known arrangements, the great advantage that sealing elements are used which, while without guides, enable the peripheral emptying ports to be absolutely sealed, even if there is dirt in the working fluid. Seizing of the sealing elements is completely eliminated by the omission of any guides. The sealing elements are almost without mass, on which account the undesirable effect of centrifugal force cannot occur. The shut-off members, which are preferably of thin iron or other metal, leather, india-rubber, or other flexible material, therefore do not require the high pressure necessary in previously known arrangements for keeping them closed while the power transmitter is full and running. The emptying ports, with their associated shut-off members, of which a plurality are provided for

each working circuit, may with the new arrangement be uniformly distributed round the periphery of the fluid circuit. The port areas available with a very shallow design are so large that a rapid exhaust of the fluid is possible. This extremely shallow design of the peripherally situated control elements, which is possible only in consequence of the mode of construction in accordance with the invention, has the consequence that the over-all diameter of the whole transmitter circuit is minimized.

Various constructional examples of the invention are shown diagrammatically in the accompanying drawings, in which:—

Fig. 1 is a section of part of a hydraulic circuit, 15 showing the control parts.

Fig. 2 is a cross section through a modified form of hydraulic turbo transmitter with a different construction of shut-off parts.

Fig. 3 is a view similar to Figure 2, but showing another modification employing tubular ports adapted to be closed by a flexible ring.

Fig. 4 is a view similar to Figure 2, but showing still another modification, wherein a bellows-operated valve is arranged to close the discharge ports, and

Fig. 5 is an enlarged, detail view of a portion of Figure 4.

In Fig. 1 ports a^1 lead from the working circuit chamber a to the atmosphere through the pressure chambers b and the passages b^1, b^2 . Liquid is admitted from the inlet pipe with its control values to the filling chamber f (as shown in Fig. 2) and thence to the working circuit chamber a of the transmitter by way of the passages e, e^1 leading to the pressure chambers b . The latter are disposed outside the working circuit chamber proper, and can be sealed from the circuit chamber a by sealing elements d . Under the influence of centrifugal force the working liquid admitted to the pressure chambers b exerts on the sealing elements d a pressure exceeding that existing in the circuit chamber a . The sealing elements d abut against annular flat seatings g and h and thereby effect a tight seal between the chamber a and the pressure chambers b . A small quantity of liquid flows back to the reservoir through regulating ports c , which is desired are adjustable by plugs c^1 . This returning liquid is renewed by the control pump during running, and the sealing elements d remain in the closed position.

When the transmitter is required to be put out of operation, the control pump is shut off or the admission of liquid is interrupted by closing the

valve *s* so that liquid is no longer fed to the pressure chambers *b*. Thereupon the pressure acting inwardly on the sealing elements *d* falls and the higher pressure existing in the circuit chamber *a* 5 raises these sealing elements *d* from their seats *g*, *h* with the result that the contents of the working circuit of the transmitter can now escape through the openings *a*¹, *b*¹ and *b*². The sealing elements *d*, which are preferably of thin sheet 10 steel or other flexible material, seat tightly on the annular surfaces *g* and *h*. The main sealing rings *g* are so arranged that dirt cannot ordinarily stick on them, since during emptying of the circuit the working liquid flows over the exposed edges with high velocity. Should a particle 15 of dirt remain attached to the annular seatings, this will be sure to be washed away during a subsequent emptying operation. A temporary slight 20 lack of tightness between the circuit chamber *a* and the pressure chambers *b* does not adversely affect the normal operation of the hydraulic circuit, since the smaller leakage losses are made good by the control pump. Ring *k* prevents the 25 sealing disks *d* from taking up a wrong position on their seats when they return. The sealing disks *d* are rendered accessible by easily removable plugs *i*. The emptying ports *a*¹ are preferably formed in the driving part of the rotatable 30 transmitter circuit, since this part in any case always rotates at the higher speed.

A further desirable constructional feature is the provision of an annular chamber *e*² leading all round the circumference of the transmitter 35 and from which the individual passages *e*¹ debouch (Fig. 1), instead of separate passages *e* to each pressure chamber *b* (Fig. 2). In the embodiment shown in Figure 1, a filling chamber (not shown) is provided similar to that shown at *f* in Figures 2, 3 and 4 and similarly referred to herein. If desired, only one passage *e* communicates 40 between the filling chamber *f* and the annular chamber *e*². The control chambers *b*, *f* and *e* are preferably kept as small as possible, their total 45 volume amounting to not more than 5 per cent. of that of the circuit. Rapid emptying of the circuit is possible only when the control chambers are kept as small as possible, because the greater part of the liquid present in the control 50 chambers must escape through the small ports *c* before the opening of the shut-off elements *d*.

Fig. 3 shows a modification of Fig. 2 wherein pressure fluid entering the control chamber *b* 55 causes flexible sealing member *d* to close the outer ends of the outwardly projecting tubular members *a*² and consequently to close the ports *a*¹. In the modification shown in Figures 4 and 60 5, the shut-off member consists of a bellows *d* limited in its motion by the screw *d*¹ and having a head *d*² adapted to close the port *a*¹. The bellows *d* has a flexible corrugated cylindrical body the outer end of which is fixed to the body *i* and, as before, provided with a passage *c* therethrough. The admission of pressure fluid 65 through the passage *e* expands the bellows *d* and causes the head *h* to prevent communication between the pressure chamber *b* and the exhaust passage *b*².

I claim:

70 1. In a hydraulic power transmitting device, a working chamber, a driving rotor and a driven rotor therein, a plurality of ports leading out of said working chamber, a control chamber communicating with each of said ports, means for supplying pressure fluid to said chambers, and

freely movable sealing laminae arranged to close said ports in response to the admission of pressure fluid to said chambers.

2. In a hydraulic power transmitting device, 5 a working chamber, a driving rotor and a driven rotor therein, a plurality of ports leading out of said working chamber, a control chamber communicating with each of said ports, means for supplying pressure fluid to said chambers, and relatively thin flexible sealing elements arranged 10 to close said ports in response to the admission of pressure fluid to said chambers.

3. In a hydraulic power transmitting device, 15 a working chamber, a driving rotor and a driven rotor therein, a plurality of ports leading out of said working chamber, a control chamber communicating with each of said ports, means for supplying pressure fluid to said chambers, freely movable sealing laminae arranged to close said 20 ports in response to the admission of pressure fluid to said chambers, and outlet ports arranged in the wall of said chambers for releasing fluid therefrom.

4. In a hydraulic power transmitting device, 25 a working chamber, a driving rotor and a driven rotor therein, a plurality of ports leading out of said working chamber, a control chamber communicating with each of said ports, means for supplying pressure fluid to said chambers, freely 30 movable sealing laminae arranged to close said ports in response to the admission of pressure fluid to said chambers, and outlet ports arranged in the wall of said chambers for releasing fluid 35 therefrom independently of the open or closed position of said sealing laminae.

5. In a hydraulic power transmitting device, 40 a working chamber, a driving rotor and a driven rotor therein, a plurality of ports leading out of said working chamber, a control chamber communicating with each of said ports, means for supplying pressure fluid to said chambers, freely movable sealing laminae arranged to close 45 said ports in response to the admission of pressure fluid to said chambers, outlet ports arranged in the wall of said chambers for releasing fluid therefrom independently of the open or closed position of said sealing laminae, and means for adjustably varying the openings of said control 50 chamber outlet ports.

6. In a hydraulic power transmitting device, 55 a working chamber, a driving rotor and a driven rotor therein, a plurality of ports leading out of said working chamber, a control chamber communicating with each of said ports, means for supplying pressure fluid to said chambers, and freely movable sealing laminae arranged to close 60 said ports in response to the admission of pressure fluid to said chambers, said working chamber outlet ports having tubular outlet members 65 adapted to be engaged and closed by said sealing laminae.

7. In a hydraulic power transmitting device, 70 a working chamber, a driving rotor and a driven rotor therein, a control chamber having a plurality of sets of adjacently disposed inlet and outlet ports, said inlet ports leading out of said working chamber into said control chamber, means for supplying pressure fluid to said chambers, and freely movable sealing laminae, each 75 laminae being arranged to close the inlet and outlet ports of a set thereof in response to the admission of pressure fluid to said chambers, said control chamber inlet ports being arranged in the peripheral wall of said working chamber whereby 80

to cause centrifugal force to eject the fluid therethrough.

8. In a hydraulic power transmitting device, a working chamber, a driving rotor and a driven rotor therein, a control chamber having a plurality of sets of adjacently disposed inlet and outlet ports, said inlet ports leading out of said working chamber into said control chamber, means for supplying pressure fluid to said chambers, and freely movable sealing laminae, each laminae being arranged to close the inlet and outlet ports of a set thereof in response to the admission of pressure fluid to said chambers.

9. In a hydraulic power transmitting device, a working chamber, a driving rotor and a driven rotor therein, a control chamber having a plurality of sets of adjacently disposed inlet and outlet ports, said inlet ports leading out of said working chamber into said control chamber, means for supplying pressure fluid to said chambers, and freely movable sealing laminae, each laminae being arranged to close the inlet and outlet ports of a set thereof substantially simultaneously in response to the admission of pressure fluid to said chambers.

10. In a hydraulic power transmitting device, a working chamber, a driving rotor and a driven rotor therein, a shaft connected to one of said rotors, a fluid reservoir adjacent said shaft, a control chamber having an inlet from said working chamber and an outlet port adjacent said inlet port, said outlet port extending at least partially around said inlet port, a relatively thin sealing laminae responsive to the admission of pressure fluid to said control chamber to extend over and close said inlet and outlet ports, and

fluid-conducting means for connecting said reservoir to said control chamber.

11. In a hydraulic power-transmitting device, a working chamber, a driving rotor and a driven rotor therein, a fluid outlet port with a valve seat leading out of said working chamber, a control chamber communicating with said port, a control passageway for supplying pressure fluid to said control chamber, and a freely movable thin flexible sealing member movable into abutment with said valve seat to close said outlet port in response to the admission of pressure fluid to said control chamber, said control passageway opening into said control chamber on the opposite side of said sealing member from said working chamber.

12. In a hydraulic power-transmitting device, a working chamber, a driving rotor and a driven rotor therein, a fluid outlet port with a valve seat leading out of said working chamber, a control chamber communicating with said port, a control passageway for supplying pressure fluid to said control chamber, and a freely movable thin flexible sealing member movable into abutment with said valve seat to close said outlet port in response to the admission of pressure fluid to said control member, said control passageway opening into said control chamber on the opposite side of said sealing member from said working chamber, the area of said sealing member exposed to the pressure fluid in said control chamber being greater than the area thereof exposed to said working chamber through said outlet port.
